CALIFORNIA.

BINDER POST.

Application filed February 21, 1927. Serial No. 170,023.

The present invention relates to improvements in posts for loose leaf binders, and the particular object of the invention is to provide a post of the character described that is longitudinally compressible so as to be adapted for compressing a number of sheets assembled in a binder, but which automatically locks against extension so that there is no means, short of breaking the post, for dis-
10 assembling the binder.

A further object of the invention is to provide means allowing the posts to be suitably extended for use in connection with a binder exceeding in heaviness the normal 15 range of the post, without defeating the object previously set forth.

Further objects and advantages of our invention will appear as the specification proceeds.

20 The preferred form of our invention is illustrated in the accompanying drawing, in which

Figure 1 shows a perspective view of a binder having our post incorporated therein;

25 Figure 2 is a vertical section through an edge portion of the binder illustrating the use of our post;

Figure 3 a detail view of our post taken by itself, considerably enlarged; and

30 Figure 4 a detail sectional view taken along line 4-4 of Figure 3.

While we have shown only the preferred form of the invention, it should be understood that various changes or modifications 35 may be made within the scope of the claim hereto attached without departing from the spirit of the invention.

In its preferred form the loose leaf binder comprises the two covers 1 and 2 having 40 wings 3 hinged thereto as at 4, and a plurality of sheets of paper 6, arranged between two covers and held between the wings 3 by means of posts 7 passing through registering perforations between the sheets and the 45 wings of the covers.

The peculiar construction of the posts is the principal feature of the present invention. As illustrated in Figure 3, our posts comprise a cylindrical portion 8 terminating 50 at the bottom in a reduced threaded end 9 and adapted to telescopingly receive a plunger 11 formed with a head 12 at the top end thereof. The plunger is hollow on the inside

and is formed near the bottom thereof with a transverse pin 13 around which passes a 55 spring 14, V-shaped in form, the two legs of the spring extending upwardly and being bent outwardly at their extreme ends, as shown at 16, to pass through apertures 17 in the walls of the plunger, and to engage with corrugations 18 in the inner face of the cylinder. The position of the spring relative to the corrugations and the arrangement of the latter are such that the projected ends of the teeth prevent the withdrawal of the plunger 60 from the cylinder, while not interfering with the telescoping engagement to any depth desired, within the range of the apparatus. The bottom end of the plunger may be temporarily or permanently closed by a plug 19. 65

The reduced threaded end 9 of the cylinder 8 may thread into the lowermost wing of the cover 2 directly, or may thread into an extension piece 21, which on its part presents a reduced threaded extension 22 adapted to 70 be threaded into the bottom wing.

The manner of using our invention should be readily understood from the foregoing description. When the extension piece 21 is used its reduced end 22 is threaded into 75 the lowermost wing 3 in the manner shown in Figure 2. The cylinder 8 is then threaded into the extension piece 21 in the manner shown in Figure 2. Thereupon, the plunger 11 is introduced through the top wing 80 and the perforations in the superimposed sheets to telescope into the cylinder. The plunger is firmly depressed until its head 12 comes in contact with the top face of the upper wing 3 and until the sheets of 85 the binder are firmly compressed between the head and the bottom end of the posts. The plunger is locked relative to the cylinder against reversal or withdrawal, so that it is impossible to take apart the loose leaf 90 binder after the posts have been applied. It will be noted that the head 12 of the post is not provided with any slot allowing of the application of a screw driver, and that the head is formed very flat so as to make it difficult to impart turning motion to the same 95 by any ordinary tool.

We claim:

A binder post of the character described comprising a cylinder formed with ratchet 105 teeth in the inner face thereof and a hollow

plunger slideable in the cylinder having a V-shaped spring therein with a pin extending transversely through the plunger and the apex of the spring and with the ends of the spring bent outwardly and projecting outwardly through the wall of the plunger for engagement with the ratchet teeth so as

to allow relative motion of the cylinder and the plunger in one direction only and a plug in the end of the plunger extending to within 10 close proximity of the pin for confining the apex of the spring therebetween.

HAROLD T. PAYNE.
